UNITED STATES PATENT OFFICE.

HERMAN PRIES, OF MICHIGAN CITY, INDIANA.

BRAKE-BEAM.

SPECIFICATION forming part of Letters Patent No. 735,296, dated August 4, 1903.

Application filed June 12, 1903. Serial No. 161,154. (No model.)

To all whom it may concern:

Be it known that I, HERMAN PRIES, a citizen of the United States, and a resident of Michigan City, county of Laporte, and State 5 of Indiana, have invented certain new and useful Improvements in Brake-Beams, of which the following is a specification and which are illustrated in the accompanying drawings, forming a part thereof.

10 This invention relates to that type of brake-beams which are in truss form, and its object is to render such beams stronger and lighter.

The invention consists in a beam of this 15 character having for its compression member a channeled bar of approximately uniform size and shape in cross-section throughout its length, a tension member having its ends bent so as to lie within the channeled bar, 20 and heads having countersunk apertures within which the ends of the compression member are fitted and through which the ends of the tension member pass, nuts being applied to the ends of the tension member so 25 as to bear against the outer faces of the heads.

This construction is illustrated in the accompanying drawings, in which—

Figure 1 is a side view of the brake-beam, partly in elevation and partly in section. 30 Fig. 2 is a detail of the strut of the truss, the compression member being shown in cross-section; and Fig. 3 is a sectional view on the line 3 3 of Fig. 1.

The compression member 10 of the brake-beam is a channeled bar of substantially 35 uniform size in cross-section throughout its length and may be of commercial rolled stock. The tension member 11 is preferably a round rod and has its ends bent so as to 40 bring them into alinement with the compression member, as shown at 16.

The heads 13, which carry the brake-shoes 14, are apertured and countersunk so that the ends of the compression member may fit within them, while the ends of the tension 45 member may pass entirely through them. Nuts 15 are screwed upon the ends of the tension member and bear against the outer faces of the heads 13. The strut 12 is apertured so as to allow both the compression and tension members of the truss to pass through it. 50

The diameter of the tension member is approximately the same as or may slightly exceed, as shown, the depth of the channeled compression member. The strain resisted by 55 the nuts 15 is by reason of the construction described transmitted centrally to the compression member, and hence the tendency of this member to buckle is much less than in the construction of the beam disclosed in the 60 Patents No. 565,060, granted to Henry C. Williamson August 4, 1896, or No. 565,879, granted to John J. Casey August 18, 1896, while the weight or cost of the beam is not increased. 65

I claim as my invention—

In a brake-beam in truss form, in combination, a pair of heads having countersunk apertures, a compression member in channel form throughout its length and having its 70 ends fitted within the apertures of the heads, a tension member having its ends bent to aline with the compression member and fitted within its channel and passing through the head-apertures, nuts applied to the ends 75 of the tension member, and a strut interposed between the compression and tension members.

HERMAN PRIES.
